FRANK A. JONES, OF OMAHA, NEBRASKA, ASSIGNOR OF ONE-HALF TO
EDWARD M. WILCOX, OF OMAHA, NEBRASKA.

ENVELOP MOISTENER AND SEALER.

SPECIFICATION forming part of Letters Patent No. 705,531, dated July 22, 1902.

Application filed April 4, 1901. Serial No. 54,305. (No model.)

To all whom it may concern:

Be it known that I, FRANK A. JONES, a citizen of the United States, residing at Omaha, in the county of Douglas and State of Nebraska, have invented a new and useful Envelop Moistener and Sealer, of which the following is a specification.

This invention relates to envelop moisteners and sealers.

10 The object of the invention is, in a thoroughly efficient, ready, and rapid manner, to moisten and seal envelopes, irrespective of their bulk or thickness.

15 The envelop moistener and sealer characterized by the present invention comprehends in this structure, generally stated, a frame or casing supporting a moistening-roller, a sealing-roller, and an endless feed-belt or conveyor for feeding the envelopes under the two 20 rollers, the motion of the belt in operation being always onward, thereby to cause the machine to be continuous in operation. The moistening-roller and sealing-roller are mounted for yielding movement with relation to the feed-belt to render these rollers 25 automatically adjustable, thus to accommodate the device to envelopes of different thicknesses or to any inequalities that may exist in the envelop. As a matter of further improvement I combine with the said rollers and the belt a bed-plate, over which the feed-belt travels, the rollers to bear upon the belt contiguous to the ends of the plate, the bed-plate 30 to be rigid, thereby preventing any sagging of the belt. As a means for imparting motion to the belt I employ two drive-rollers 35 suitably mounted for movement on journals mounted in bearings in the side of the casing contiguous to each end of the bed-plate, the upper faces of the drive-rollers to be in line approximately horizontal with the bed-plate to prevent interference between the bed-plate and the belt in the operation of the machine. The moistening-roller is a hollow 40 structure provided with numerous perforations, through which water will be fed to the wick or cover, the roller being provided with a fixed end and a removable end, the latter by preference having a threaded connection 45 with the roller to permit of its removal when the roller is to be filled with water.

Another and highly important feature of the present invention is to dispense with the flap-folding device commonly located between the moistening and sealing elements, 55 so as to materially simplify the device, and to construct and arrange the moistening and sealing elements so as to permit of the envelop-flaps folding or curling up of themselves after being moistened and preparatory 60 to engagement with the sealing element.

As a matter of further improvement I provide means to prevent unnecessary dampening of the feed-belt when the machine is not in use. To effect this, the journal-bearings 65 of the moistener-roller are formed by two slots disposed at an angle to the bed-plate, the lower end of each slot being formed with a depression in which the journals of the roller work when the machine is in operation 70 and the upper end of each slot being formed with similar depression in which the journals rest when the machine is not in use, and when the roller is in this latter position it is free from contact with the feed-belt. 75

The moistening-roller may be driven by a crank carried by the shaft of the drive-roller mounted under the moistening-roller, as shown, or by foot-power or otherwise. Where power is used for driving the device, this may 80 be effected by mounting a pulley on the shaft of the drive-roller, the pulley to be connected with any suitable source of driving power, as a pedal-wheel or a motor.

Further and more specific details of construction will be hereinafter pointed out. 85

In the accompanying drawings, forming a part of this specification and in which like numerals of reference indicate corresponding parts, I have illustrated a form of embodiment of my invention capable of carrying my ideas into effect, it being understood that other forms of embodiment thereof may be employed without departing from the spirit of the invention, and in these drawings— 90 95

Figure 1 is a view in perspective exhibiting the machine as it appears when ready for use. Fig. 2 is a longitudinal vertical section taken through the center of the machine. Fig. 3 is a longitudinal section taken through the 100 moistening-roller, showing the manner in which the same is constructed.

Referring to the drawings, 1 designates the supporting frame or casing of the device, the same to be of any preferred shape and constructed of any suitable material. Generally, 5 from a standpoint of cheapness and as presenting non-corrosive qualities, the frame may be made of galvanized iron. As here shown each side of the frame is of approximately pyramidal shape in elevation; but it 10 is to be understood that I do not limit myself to this particular form, as the same may be varied without departing from the spirit of my invention. Working in suitable bearings in the sides of the frame are two rollers 2 and 15 3, the roller 2 constituting the moistening-roller and the roller 3 the sealing-roller, the rollers being spaced apart such distance that the roller 3 will always grip the envelop before it is released by the roller 2, thus insuring 20 positive movement of the envelops through the machine irrespective of their width. The moistening-roller is, as before stated, a hollow structure provided with a plurality of perforations 3^a, through which water contained in the roller in operation will be fed to the wick or cover 4, which latter may be of any suitable soft and porous fabric capable by capillary attraction to absorb and distribute water evenly throughout its entire area. The 25 roller is provided with a closed end 5, carrying a journal 6, and with a removable end 7, carrying a journal 8, the end 7 by preference having a screw-threaded connection with the roller to permit of its being readily removed 30 when the roller is to be filled with water. The sealing-roller 3 may be a hollow structure or be made solid and is provided with a cover 9 of suitable flexible fabric or any other material to suit the purpose. The journal- 35 bearings for the moistening-roller are formed by two slots 10, disposed at an upward inclined angle with relation to the plane of movement of the feed-belt 11, each slot being provided at its lowest end with a depression 12 and at its highest end with a similar depression 13. When the machine is at work, the journals of the moistening-roller 40 occupy the lower depressions 12; but when the machine is at rest the roller is shifted to 45 bring the journals into the upper depression 13, at which point the wick or cover of the roller is out of contact with the feed-belt. This arrangement is provided to prevent undue moistening of the feed-belt, which would 50 result were the wick allowed to remain in constant contact with the belt. Aside from this the water would be rapidly exhausted in the roller, thereby requiring its being re-filled oftener than necessary. The journal- 55 bearings 14 of the sealing-roller are vertical slots, this arrangement being adopted to permit the roller to yield vertically to adjust itself to envelops of different thicknesses. In order that the two rollers shall be pressed 60 with requisite stress upon the envelop to cause in the case of the moistening-roller

proper dampening of the envelop and in case of the sealing-roller to cause this to bear with sufficient pressure upon the flap of the envelop to effect perfect sealing, the two rollers are spring-pressed downward. The arrangement of springs for effecting this result herein shown is one of many that may be employed and is given as an illustration of one way of carrying out the idea, it being understood that I do not limit myself to this precise arrangement, as it will be obvious that the results attained thereby may be accomplished in many other ways. As here shown, an ordinary spring 15 is employed, one on 8c each side of the frame, and held in place against the frame by a screw or rivet 16, the ends of the springs bearing upon the top of the journals of the moistening-roller and of the sealing-roller. 85

The mechanism for imparting motion to the belt, which latter may be made of any suitable material, preferably of canvas or the like, consists of two rollers 17 and 18, the roller 17 constituting in this instance the 90 driving-roller, as it is from this that motion is imparted to the belt through the medium of a crank 19. Instead of employing a crank the shaft of this roller may be provided with a pulley, around which will pass 95 a belt to a suitable source of power, as to a pedal-wheel or to a motor, and as this arrangement will be readily understood illustration is deemed unnecessary. Rigidly mounted with regard to the sides of the frame 100 and in a plane approximately parallel or in line with the upper faces of the rollers 17 and 18 is a bed-plate 20, the ends of which terminate contiguous to the two rollers last named, the plate to be of any suitable material, preferably of galvanized iron or brass 105 on account of non-corrosive properties. The plate may be permanently attached to the frame or be detachable therefrom. In the operation of the device the moistening-roller 110 and sealing-roller press the driving-belt upon this bed-plate, so that when envelops are being fed through the machine there can be no yielding of the belt at the point where the envelops pass under the moistening-roller or 115 under the sealing-roller, or, in fact, at any point between these two rollers. At each end of the frame a table or platform 21 is provided, over which the envelops pass in being fed to and on leaving the machine. 120

All the parts of this machine are constructed with a view to durability and effectiveness in use and are so constructed and assembled as to present a device of great simplicity in construction, whereby danger of 125 derangement in use will be practically obviated.

In the operation of the machine the moistening-roller is removed from its bearings, the end 7 unscrewed, and the roller filled with 130 water, after which the end 7 is screwed into position and the roller put back in place.

As soon as the roller is positioned the water contained therein will be fed to the wick or cover through the openings 3, thereby imparting sufficient moisture immediately to effect moistening or dampening of the envelops. The envelops are then taken, with the flap turned out, and passed under the moistening-roller flap foremost, where the mucilage on the flap will be wetted before any other part of the envelop passes under the roller 2. In its passage under the roller the flap is curved upward toward the body of the envelop, thereby bringing it into position to be engaged by the sealing-roller, which will in a manner readily understood force the flap down against the envelop and effect perfect sealing.

One of the important features of the present invention resides in the peculiar relation of the moistening and sealing elements, whereby the flap is permitted to curl upwardly for proper engagement with the sealing element. The most effective relation of these elements is to have the same separated by a space, the greatest length of which is less than the width of the envelop and the shortest length is at least equal to the width of the sealing-flap of the envelop, as said flap is held relatively close to the endless belt 11 until it is freed from the moistening-roller, whereby it is apparent that the sealing-roller should be spaced from the moistening-roller at a distance at least equal to the width of the sealing-flap in order that said sealing-roller may not engage the flap until it has curled sufficiently to be effectively folded over by the sealing-roller. Hence this relative arrangement of the moistening and sealing elements provides means for folding the envelop-flaps after the moistening thereof and preparatory to engagement with the sealing element.

Where the device will be driven by power, the frame will be secured upon a table; but where used by hand it will be unattached from any support, to permit of its being transported at will.

Having thus described the invention, what I claim is—

- 50 1. In an envelop moistener and sealer, the combination of means for moistening envelop-flaps while they are open, means for feeding envelops to and from the moistening means with the flaps open and in advance, and means for applying pressure to the flaps to seal the same after they have passed beyond the moistening means but before the bodies of the envelops have cleared said means.
- 60 2. In an envelop moistener and sealer, the combination of an endless feed-belt, a moistening device coöperating transversely with the belt and at least equal in length to the length of an envelop-flap, and a pressure device coöperating transversely with the belt to seal envelop-flaps, and at least equal in length

to the length of an envelop-flap, the moistening device and the pressure device being spaced at a distance less than the width of an envelop and more than the width of an envelop-flap.

3. In an envelop moistener and sealer, the combination with an endless belt, of a moistening-roller disposed transversely in frictional engagement with the belt and extending for substantially the width thereof, and a pressure-roller disposed transversely in frictional engagement with the belt and extending substantially for the width thereof, the distance between the two rollers being less than the width of an envelop and more than the width of the sealing-flap thereof, whereby the forward edge of an envelop is engaged between the pressure-roller and the belt before the rear edge thereof has become disengaged from between the moistening-roller and the belt.

4. In an envelop moistener and sealer, the combination with a back, of an endless conveyer-belt traveling across the back, a moistening-roller in frictional engagement with the front end portion of the belt and extended transversely for substantially the width thereof, and a pressure-roller extending transversely in frictional engagement with the belt and for substantially the entire width thereof, the pressure-roller being located in rear of the moistening-roller at a distance less than the width of an envelop and more than the width of the sealing-flap thereof, whereby the forward edge of an envelop is engaged between the pressure-roller and the belt before the rear edge thereof has become disengaged from between the moistening-roller and the belt.

5. An envelop moistener and sealer comprising a frame or casing carrying a bed-plate, a moistening-roller, the journals of which are mounted in slots arranged at an upward inclined angle to the bed-plate, a sealing-roller the journals of which are mounted in vertical slots, said rollers being separated by a space which is less than the width of an envelop, two-armed springs secured to the sides of the casing and bearing upon the journals of the two rollers, two drive-rollers journaled contiguous to the ends of the bed-plate, an endless belt passing over the bed-plate and around the drive-rollers, and means for imparting motion to one of the drive-rollers.

6. An envelop moistener and sealer comprising a frame or casing carrying a bed-plate, a moistening-roller having its journals mounted in slots arranged at an upward angle to the bed-plate, the journals of the roller, when in operation, occupying the lowest portion of the slots, and when out of operation, the highest portion of the slots, thereby to lift the moistening-roller above the plane of the bed-plate, a sealing-roller the journals of which are mounted in vertical slots in the frame or casing, said rollers being separated by a space

which is less than the width of an envelop, springs for exerting downward pressure on the journals of the two rollers, driving-rollers journaled contiguous to the ends of the 5 bed-plate, an endless belt passing over the bed-plate and around the rollers, and means for imparting motion to one of the rollers.

In testimony that I claim the foregoing as my own I have hereto affixed my signature in the presence of two witnesses.

FRANK A. JONES.
